COMPRESSSIONAL WAVE SENDER OR
RECEIVER

Willy Kunze, Bremen, Germany, assignor to Submarine Signal Company, Boston, Mass., a corporation of Maine

Application September 9, 1933, Serial No. 688,770
In Germany December 24, 1932

3 Claims. (Cl. 177—386)

The present invention relates to underwater sound receivers and transmitters and more particularly to such instruments employing piezo-electric crystals.

In the past the piezo-electric properties of quartz have been employed for sending and receiving sound waves in water. However, quartz instruments have had a number of disadvantages which were particularly noticeable when used for receiving. On the one hand, the piezo-electric effect of quartz is comparatively weak so that great amplification had to be resorted to in order to obtain the necessary results. On the other hand, quartz is a comparatively expensive material which usually can be obtained in only relatively small crystals which, therefore, must be assembled by special means in a mosaic fashion to produce senders or receivers of reasonable size. Practical results can only be obtained with quartz if the natural resonance of the crystals is made use of.

It has been known that substantially better piezo-electric operation can be obtained with certain other crystals, for example, of such salts as sodium potassium tartrate which are also known as Rochelle-salt crystals. Experiments have shown that the use of Rochelle-salt crystals is particularly advantageous for receiving sound in water.

One object of the present invention is to provide for submarine sound senders and receivers a means for utilizing the piezo-electric effect of Rochelle-salt crystals for the transformation of compressional vibrations into electric vibrations, and vice versa. Rochelle-salt crystals can readily be produced in comparatively large sizes and are relatively cheap. Their special value lies, however, in the fact that as compared with the piezo-electric materials which have been used in the past Rochelle-salt crystals produce especially energetic effects.

The conditions attending sound transmission under water are not accompanied by comparatively large amplitudes of the medium with relatively small pressure changes as is the case in air, but vice versa with large pressure changes and small amplitudes. For this reason a Rochelle-salt crystal is particularly advantageous since it responds well to pressure variations, and it is especially good for underwater sound receivers. Since these crystals have no natural frequency in the audio frequency range, it is possible by means of these crystals to build submarine sound receivers which can receive over the entire audible frequency range without distortion.

They are consequently very well adapted for noise reception. If they are to be used for signal reception, then care must be taken by suitably dimensioning the crystal with respect to the cooperating metal elements that oscillatory systems result whose natural frequency coincides with the signal frequency.

Rochelle-salt crystals are soluble in water. It is for this reason necessary to place them in a watertight housing. The crystals are preferably cut to provide two surfaces which are perpendicular to an electrical axis and to permit the compressional wave vibrations to act upon the surfaces. The receivers can be so built that only one surface is acted upon by the pressure waves while the other surface of the crystal is rigidly fastened to a fixed mass in the housing, or alternatively both surfaces may be arranged to be acted upon by the pressure waves in the water.

Further features of the invention will be apparent from the description of the arrangement shown in the drawing in which Fig. 1 shows a double diaphragm transmitter or receiver and Fig. 2 shows a plan view looking at Fig. 1 from the bottom; Fig. 3 shows in vertical section a modification of the device shown in Fig. 1; and Fig. 4 is a horizontal section of the modification shown in Fig. 3; Fig. 5 shows a further modification in which a single thin rubber diaphragm is used to conduct the vibrations to and from the crystals and the water.

A simple construction of a Rochelle-salt sender or receiver is shown in Fig. 5 in which the radiating surface of the crystal is covered with a thin rubber diaphragm which protects the crystal chamber from the water. A rather massive pot-shaped metallic housing 1 contains the crystal 2 which is mounted so that one surface 3 is rigidly held against the back wall of the housing 4 which is in the form of a rigid mass. The other surface 4 projects slightly from the opening of the housing. The surface 4 is covered by a diaphragm 5, for example, of rubber whose outer edge is tightly clamped to the housing by a clamping ring 6. Care is taken that there is substantially no space between the crystal and the walls of the housing in which a pressure release could take place. Two metal plates 7, for example, in the form of leaf springs, press lightly against the crystal and act as electrodes. They are fastened to the housing by means of insulating members 8. Two conductors 9 and 10 lead out of the housing and connect with cable 11.

Sound waves in water striking the rubber dia-

phragm 5 are transferred to the crystal 2 and by virtue of the piezo-electric effect produce corresponding electrical potential variations at the electrodes 7, which are conducted to an amplifier 5 and made audible in this manner.

If the two conductors are connected to the terminals of an alternating current source, the receiver may be used as a sender. To increase the piezo-electric effect while receiving it may 10 be desirable to apply to the electrodes a polarizing potential. It should be noted, however, that the diaphragm 5 produces in itself a definite constant initial pressure upon the crystal, thereby giving it a pressure polarization.

15 If the surface covered by the crystal is sufficiently large, one obtains a sharp directional effect, that is to say, when the wave length of the sound is small with respect to the dimensions of the diaphragm.

20 A double-diaphragm instrument is shown in Figs. 1 and 2. In these figures 1 is a rigid housing closed at one end by a piston diaphragm 2 forming part of the housing and closed at the other end by a cover 4 which also forms the 25 piston diaphragm 3. Between the piston diaphragms is mounted the Rochelle-salt crystal 5. 6 and 7 are electrodes, for example, thin metal foil mounted on the crystal by suitable adhesive and connected to the conductors 8 and 9 which 30 serve to conduct electric energy to and from the crystals. The inner surfaces of the piston diaphragms 2 and 3 are separated from the crystal by insulating layers 10 and are pressed tightly against the crystal by the tension of the dia- 35 phragms.

It will be noted that the areas of the diaphragms are large compared with the areas of the active surfaces of the crystal. This has the effect of greatly increasing the sensitivity of the 40 device when used as a receiver.

The increased sensitivity by virtue of the larger radiating surface can also be obtained by means of the modification shown in Figs. 3 and 4. In this case the radiating surfaces are semi- 45 cylindrical in form. In Figs. 3 and 4 the Rochelle-salt crystal 5 is mounted between two semi-cylindrical rigid bodies 11. On the other hand, the members 11 may be made of insulating material. The members are held together by a shell 12 which may be of rubber and designed 50 to press the members 11 tightly against the surfaces of the crystal 5. 13 and 14 are two metal plates which serve as holding members for the shell 12 which is clamped to them by means of 55 the rings 17 and 18 which press the shell 12 into grooves 15 and 16 in the members 13 and 14. The whole arrangement is in this manner made watertight.

It will be observed that the curved surfaces 60 of the members 11 serve as radiating surfaces while the internal surfaces of the members 11 are made flat and are pressed against the crystal. In order that the members 11 may each vibrate as nearly as possible as a whole and 65 transfer the pressure with best efficiency to the crystal 5, they are separated by a small air space. However, the use of the shell 12, as shown in Figs. 3 and 4, is thought to be preferable and avoids the necessity of filling the spaces between 70 the members 11, so that they can vibrate freely.

In the devices according to the present invention care should be taken to avoid any looseness between the diaphragm and the crystal or between the crystal and the back plate in order that 75 the pressure variations may be efficiently trans-

ferred to the crystal. To this end the crystal may be mounted on the housing or the diaphragm by a suitable adhesive or by other suitable means.

It has been found that with the described devices distortionless reception with sufficient sensitivity may be obtained up to 20,000 cycles per second. The devices are therefore particularly useful for the receipt of frequencies in the vicinity of or above the audible range. They are also useful for noise reception on account 10 of their large frequency range. Whenever it is necessary that the received sound vibrations be transformed into electrical vibrations with as nearly the same phase relations as possible as is, for example, the case with group of the so-called 15 multispot listening arrangements, the receivers according to the present invention are particularly advantageous.

Also when used in a device towed by a moving vessel, for example, in which a plurality of receivers are arranged in a straight line at equal distances from one another, the receiver according to the present invention is of particular advantage on account of its freedom from disturbing noises. In this case the individual receivers 20 are preferably enclosed within a common shell as, for example, a rubber housing which protects the receivers from the water and holds them at the proper distances from one another.

It will be understood that the present invention may be used for producing sound waves in water by applying a potential to the electrodes.

Having now described my invention, I claim:

1. A compressional wave submarine sender or receiver comprising a housing closed at one end 35 by a heavy mass and having an opening at the other end, a Rochelle-salt piezo-electric crystal, having electric and compressional axes, mounted therein in contact with said mass and with its compressional axis perpendicular to the plane of said opening, a yielding rubber-like diaphragm in contact with said crystal and covering said opening, said diaphragm having a thin portion between the place of contact of the crystal and the edge of the opening, and means for conducting 40 electric energy to or from the electric axes of said crystal.

2. A compressional wave submarine sender or receiver comprising a housing closed at one end by a heavy mass and open at the other end, a Rochelle-salt piezo-electric crystal having electric and compressional axes mounted so that one compressional surface abuts said end mass and its opposite surface projects slightly through said opening, a rubber sheet, means for stretching 50 said sheet over said opening and said projecting crystal surface, whereby the crystal is pressed firmly against the end mass of the housing, and means for conducting electric energy to and from 55 said crystal.

3. A compressional wave submarine sender or receiver comprising a casing having a heavy back wall and heavy sides and open at one end, a Rochelle-salt piezoelectric crystal substantially filling the interior of the casing and supported 65 against the back thereof, said crystal having its compressional axes normal to the casing and extending substantially to the end surfaces of the sides thereof, a thin yielding diaphragm covering the open end of said casing and means 70 clamping said diaphragm in position, said clamping means extending substantially to the edges of the inner wall of said opening.
